United States Patent Office

Des. 228,973
Patented Oct. 30, 1973

228,973

ARTICLE STORAGE UNIT

Raymond A. Waldsmith, Folsom, Calif.
(1531 Forni Road, Placerville, Calif. 95667)

Filed Oct. 28, 1971, Ser. No. 193,611

Term of patent 7 years

Int. Cl. D3—99

U.S. Cl. D87—1 R

FIG. 1

FIG. 2

FIG. 3

FIG. 1 is a front perspective view of an article storage unit showing my new design;

FIG. 2 is a side elevational view showing the side opposite that seen in FIG. 1; and

FIG. 3 is a front elevational view thereof.

I claim:

The ornamental design for an article storage unit, substantially as shown and described.
